UNITED STATES PATENT OFFICE

GEORGE F. EGAN, OF JERSEY CITY, NEW JERSEY

SEWER CONSTRUCTION

Original application filed July 31, 1925, Serial No. 47,281. Divided and this application filed April 9, 1926. Serial No. 100,989.

The present invention relates to improvements in sewer construction and constitutes a division of my similarly entitled co-pending application, Serial No. 47,281, filed July 31, 1925.

An object of the invention is to provide a sewer construction having a guard therein for arresting bodies, and in providing, in conjunction with the guard, a man-hole giving access to the guard and whereby bodies arrested by the guard may be withdrawn from the sewer.

Another object of the invention lies in providing guard means for trapping bodies to indicate where such bodies have been thrown into the sewer.

The invention further aims to provide a guard which admits of ready opening and closing and which may be left in the permanently open position if desired.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a vertical sectional view taken through a catch basin, sewer system and a guard arrangement constructed in accordance with the invention described and claimed herein;

Figure 2 is a cross sectional view taken through the sewer adjoining a guard;

Figure 3 is a vertical section taken on the line 3—3 in Figure 2;

Figure 4 is a view similar to Figure 2, showing another form of guard; and

Figure 5 is a vertical section taken on the line 5—5 in Figure 4.

Referring more particularly to Figure 1 of the drawings, 48, 48a designates a perforated cover the horizontal part of which is shown as seated upon a shoulder 49 of the horizontal part of a frame 50. The frame 50 is shown as fitted upon the upper end of the wall 51 of a basin 52. The vertical part 48a of the cover will extend up within an opening 50 in the curb. The horizontal part 48 of the

cover is shown as provided with trunnions adapted to enter suitable slots in the horizontal part of the frame 50. The curb is shown as provided with a cut out portion 54. By raising the horizontal part 48 of the cover 55 the cover as a whole may be rocked on the trunnions and the opening into the receiving basin may be uncovered. When the horizontal part of the cover has been rocked sufficiently far it will rest against the curb. The 60 raising up of the horizontal part 48 will cause the vertical part 48a to move in the cut out portion 54 and this cut out portion 54 will be so shaped as not to interfere with the movement of the vertical part 48a therein. While 65 the cover 48, 48a is shown as circular in shape it will, of course, be understood that the cover may be of any desired shape and that the frame 50 may be made to conform to the shape of the cover. 70

As much of the basin as may be desired may be built under the sidewalk leaving only, if desired, an opening in the street sufficiently large to permit an operator to enter the basin, and, if desired, instead of a perforated cover 75 of the type shown in the drawings any suitable opening and cover to the basin may be provided.

Within the basin 52 there is shown a ladder 80 appropriately supported to enable operators to descend into the basin when the cover of the basin is lifted. Pipes 59, 60 and 61 are shown as leading downwardly and out of the basin 52 at various elevations. The pipe 61 is shown as leading into the pipe 85 60 and may be a V-shaped pipe if desired. The pipe 60 is shown as connecting with a sewer indicated at 62. The pipe 63 leads downwardly and into the basin 52 and may carry fluid from another basin or any higher 90 level. The pipes 60 and 61 may be made in one piece if desired.

The sewer 62 is shown as provided with a guard 64, this guard being shown as in the shape of a perforated door hinged at its 95 upper end as indicated at 65. While I have shown the guard 64 as hinged at 65 the guard 64 may be hinged at any desired point in the upper part of the sewer. The guard 64 may abut at its lower end against a step 66 which 100

will restrict swinging movement of the door to maintain the door across the sewer and arrest large material passing through the sewer. The door 64 is shown as provided with an eye 68 with which a hook 67 may engage to hold the door elevated when its use is not desired. The hook 67 may be pivotally mounted at any appropriate point in the sewer. The sewer is accessible through a man hole 68' in which is shown as placed a ladder 69, the man hole being shown as closed at the surface by a cover 70. An extension ladder 71 may be provided to let down into the sewer from the man hole.

15 The guard 64 is desirable for discovering bodies that may have been thrown into a sewer and for locating the points at or about which these bodies were deposited. The pipes 59, 60 and 61 leading away from the basin 52 may be provided with traps consisting of perforated plates 83 arranged over the mouths of the pipes and doors 86 perforated at their lower portions as indicated at 90. These traps form the subject matter of a separate application.

19 In Figures 2 and 3 a slightly different form of guard is shown. In these figures 73 designates a ring, shown as having openings therein and as having a central orifice normally closed by a pair of doors 74 and 75, the doors being shown as of an open work construction, and as being hinged, as indicated at 76 and 77, to opposite portions of the ring 73. A latch 78 is shown as provided for holding 35 the doors in a closed position. The doors may be opened whenever necessary or desirable. As shown in Figure 2, the latch 78 may be pivoted at one end and swung upwardly to engage over depending alined projections carried by the doors 74 and 75, although any other desired fastening means may be used in the combination for securing the doors in closed position if desired.

45 While the doors are shown as rounded, the ring 73 may be so shaped that the door intended to fit in the ring may be made rectangular or in one piece, and the door may be hinged to a side or upper part of the ring.

50 In Figures 4 and 5 a further form of door is shown. In these figures 79 indicates a sewer shown as rectangular in cross section and as having a rectangular door 80 mounted therein and hung from a pintle 81 above. In this case there is shown a stop 82 against 55 which the lower free end of the rectangular door may abut. The door is shown as provided with numerous slots therein for the passage of fluid. Instead of hanging the door from the pintle 81 the door may be 60 hinged to one side of the sewer.

65 It will, of course, be understood that instead of using stops as 66 or 82 at the bottom of a sewer, stops might be provided at the sides or any other suitable points in the sewer, or the sewer might be provided with a shoulder

against which the guard might abut, and, instead of a latch, as 78, the ring 73 might have a shoulder formed thereon against which the guard may abut.

70 It will, of course, be understood that sewers are ordinarily constructed with an incline towards the point of discharge and this inclination of the sewer will tend to hold the guards closed. When guards are used in sewers so constructed no means need be provided for holding the guards in closed position, but, if desired, any suitable means might be provided to aid in holding the guards closed.

75 It is obvious that various changes and modifications may be made in the details of construction and design of the above specifically described embodiment of this invention without departing from the spirit thereof.

80 What is claimed is:—

85 1. In a subterranean sewer, a sewer pipe, a manhole leading from the surface down to the sewer pipe, a foraminous guard located in the sewer pipe at the remote side of the man-hole with reference to the direction of flow of 90 the water, means whereby said guard is pivotally supported for opening movement against the current of water, and means for holding the guard secured in the closed position.

95 2. In a subterranean sewer, a sewer pipe, a manhole leading to the pipe, a perforated guard secured in the pipe adjacent the man-hole, a pair of pivoted doors mounted in said guard and adapted to abut against the parts 100 of the guard, and means engaging alined portions of the closed doors for securing same in closed position.

105 In testimony whereof I affix my signature.

GEORGE F. EGAN.
